(57) **CLAIM**

The ornamental design for a hose bib valve, as shown and described.

DESCRIPTION

FIG. 1 is a perspective view of a first embodiment of a hose bib valve in accordance with the present invention.

FIG. 2 is a front elevational view of the hose bib valve shown in FIG. 1

FIG. 3 is a left side elevational view of the hose bib valve shown in FIG. 1, the right side elevational view is a mirror image thereof;

FIG. 4 is a rear elevational view of the hose bib valve shown in FIG. 1;

FIG. 5 is a top plan view of the hose bib valve shown in FIG. 1;

FIG. 6 is a bottom plan view of the hose bib valve shown in FIG. 1;

FIG. 7 is a perspective view of a second embodiment of a hose bib valve in accordance with the present invention;

FIG. 8 is a front elevational view of the hose bib valve shown in FIG. 7;

FIG. 9 is a left side elevational view of the hose bib valve shown in FIG. 7, the right side elevational view is a mirror image thereof;

FIG. 10 is a rear elevational view of the hose bib valve shown in FIG. 7;

FIG. 11 is a top plan view of the hose bib valve shown in FIG. 7; and,

FIG. 12 is a bottom plan view of the hose bib valve shown in FIG. 7.

The broken lines showing environment are for illustrative purposes only and forms no part of the claimed design.
